[57] ABSTRACT

Known rotating spectrophotometers have a series of cuvets arranged in a ring member concentrically around a horizontally rotatable disc so that when the disc is rotated, centrifugal force mixes and transfers reagents and samples to the cuvets. As each cuvet passes a light source, the absorbence of each individual sample is detected and measured photometrically, and is converted to an electrical signal pulse.

Upon completion of the measurements it is necessary to empty the cuvets and it is important that dispersion of the cuvet contents be avoided to prevent unsanitary and otherwise undesirable conditions. This is accomplished in the present invention by forcing the contents of the cuvets into a concave ring shaped member attached to the cuvette ring where the expelled liquid is held and confined.

**DEVICE FOR COLLECTING THE CONTENTS OF
CUVETS IN A ROTATING
SPECTROPHOTOMETER ANALYZER**

The invention relates to a device for collecting liquid from the cuvets of a rotating spectrophotometer.

In recent years, the need for rapid, automatic analytical devices has increased markedly, owing to the numerous microanalytical studies in biochemical research, routine clinical testing for physicians and hospitals, enzymatic studies, and the like.

Recently, multistation analytical photometers which utilize a centrifugal field have become available for the rapid microanalysis of a wide variety of liquids such as blood serum and other body fluids, food products, and the like. Since numerous analysis can be performed rapidly and simultaneously, these devices are of particular interest wherein a large number of samples is involved or a variety of tests on one sample is desired.

One such device which utilizes a centrifugal field in microanalytical studies is described in "Analytical Biochemistry," 28, 545-562 (1969). This device employs the principle of doublebeam spectrophotometry wherein absorbencies of a liquid sample and a reference solution are intercompared. The system is basically a series of cuvets arranged around the periphery of a rotor so that when it is spun, centrifugal force simultaneously mixes and transfers reagents and samples to the cuvets where an analysis is made spectrophotometrically. A sample loading disc is provided which contains rows of cavities arranged concentrically. Reagents are placed in the inner cavities, and the samples to be analyzed are placed in cavities at a greater radial distance than those containing the reagents. The sample loading disc is then indexed and positioned in the rotor with each individual reagent and sample system having a corresponding cuvet. As the rotor is accelerated, centrifugal force moves the reagent to the cavity containing the sample, where they are mixed and the mixture of reagent and sample is then moved by centrifugal force through a communicating passage into the cuvet. The filled cuvets rapidly spin past the fixed light beam, and the transmission of light through the cuvets, i.e., through the samples, is measured.

Upon completion of the measurements of the samples, it is necessary to remove the liquid samples from the cuvets so that measurements can be made on new samples. In the past, pressurized air has been employed to force liquid from the cuvets into the housing surrounding the analyzer and exhaust devices were employed in an effort to remove the dispersed and atomized liquid. This was a difficult task and a potential biological and sanitary hazard was always present.

Accordingly, it is an object of the present invention to provide a device for the removal and collection of liquid samples from a rotating photometric analyzer.

Other objects of the invention will be apparent from the following description and appended drawings and claims.

In the Drawings

FIG. 1 shows an elevational cross-section view of a rotating photometric analyzer incorporating the collecting device of the present invention.

FIG. 2 is a partial plan view of a sample disc and cuvet ring of a rotating photometric analyzer and FIG.

3 shows an isometric view of portion of the collecting device of the present invention.

With reference to the drawing, FIG. 1 shows in elevation a rotating photometric analyzer comprising a removable sample-reagent disc 10 supported on a rotor 11 and suitably indexed thereto (not shown). Rotor 11 is affixed to drive assembly 12 by pin 15. Drive assembly 12 is rotatably driven by way of v-belt pulley 13 attached to drive shaft 17. The portion 16 of rotor 11 is suitably of stainless steel over which is arranged a glass plate 18. The body portion 20 of sample-reagent disc 10 is suitably formed of Teflon (Trademark of E. I. DuPont de Nemours) and contains a plurality, usually about 30, of concentrically arranged inter-connecting cavities indicated at 22. Reagent cavity 24, contains for example a glucose reagent such as a 0.3 molar triethanolamine buffer of pH 7.5 containing 0.0004 Mol/liter NADP, 0.0005 Mol/liter ATP, 70 mg/liter hexokinase, 140 mg/liter glucose-6-phosphate dehydrogenase and 0.004 Mol/liter MgSO₄. The reagent, indicated at 26, upon spinning of the sample-reagent disc 10, passes into sample cavity 28, containing for example blood serum, and both liquids pass via transfer passage 30 into cuvette 32 located in ring member 34 which is affixed (not shown) to rotor 11. Cuvette 32, and all other cuvettes, are enclosed by ring member 34. Ring member 34 is suitably formed of aluminum. The extent of the reaction between the liquids in cuvette 32 is measured photometrically by means of light source 38 and photomultiplier 40 in accordance with known techniques.

As shown in FIG. 1, the rotating photometric analyzer is substantially enclosed by metal housing 48, plastic ring shield member 51 and plastic cap member 52, which encloses sample reagent disc 10 containing cavities 22.

In accordance with the present invention, and with reference to FIGS. 1 and 3 in particular, a collecting ring 50 suitably made of aluminum if fixedly attached to cuvet ring member 34 and is rotatable therewith upon actuation of drive assembly 12.

Upon completion of the measurements for the liquid 33 in cuvettes 32, and while cuvet ring member 34, and attached collecting ring 50, are still rotating, pressurized gas, e.g., forced air, is introduced via conduit 45 60 into passageway 64 of drive assembly 12, conduits 66 in enclosed sample-reagent disc 10. The forced air is used to move cuvet liquid 33, previously confined within cuvets 32 and siphon arms 80, to siphon arms 82. Due to the siphon arrangements 68, communicating via conduits 70 with cuvets 32, the cuvet liquid 33 moves to the outer surface of cuvet ring 34. The forced air forces the cuvet liquid to the outer surface of the cuvet ring 34 where centrifugal force developed by rotation of the cuvet ring 34 causes the expelled cuvet liquid 71 to be thrown against the generally concave surface 72 of annular collecting ring 50 and held by centrifugal force in a relatively narrow and confined zone. Upon discontinuing rotation, the cuvet liquid 71 falls by gravity over restraining edge 75 into drain ring 77 from which it can be conveniently withdrawn via conduit 79 utilizing conventional pumping mechanisms. In the device of the present invention, the air space in the annular passage 90 is essentially static with respect to the expelled cuvet liquid since collecting ring 50 and cuvet ring 34 rotate together. Thus the spattering and atomization of liquid, which would occur due to turbulent air conditions if collecting ring 50 were stationary,

is avoided. Spattering is further minimized by arranging the collecting ring 50 such that the expelled cuvet liquid strikes the collecting ring at acute angle to the tangent of the collecting ring surface as indicated at 92.

As can be seen, dispersion and atomization of cuvet liquid is avoided whereby the threat of toxic and unsanitary conditions are eliminated. Also, interference with the optical system and other mechanisms of the analyzer is avoided. Also, the device of the present invention is self-balanced in both the empty and filling conditions. Further, the device of the present invention is uncomplicated, inexpensive and requires no maintenance.

What is claimed is:

1. In a rotating spectrophotometric chemical analyzer including a rotating cuvet ring having an outer surface and having cuvettes in communication with said outer surface, said cuvettes being adapted to contain liquid, the improvement for collecting liquid from the cuvettes which comprises means for forcing the liquid in said cuvettes to the outer surface of said rotating cuvet ring to enable the centrifugal force developed by said cuvet ring to separate said liquid from said cuvet ring and collecting means fixedly positioned with respect to said rotating cuvet ring and rotating therewith having a generally concave inner surface opposite said cuvettes arranged to restrain and confine liquid separated from

said cuvet ring within said collecting during rotation of said cuvet ring.

2. In a rotating spectrophotometric chemical analyzer including a rotating cuvet ring having an outer surface and having cuvettes in communication with said outer surface, said cuvettes being adapted to contain liquid, the improvement for collecting liquid from the cuvettes which comprises conduit means communicating with each of said cuvettes and the outer surface of said cuvet ring and arranged whereby liquid is retained in said cuvettes and said conduit means; means for applying pressurized gas to said cuvettes to force the liquid in said cuvettes through said conduits to the outer surface of said rotating cuvet ring to enable the centrifugal force developed by said cuvet ring to separate said liquid from said cuvet ring; and an annular collecting member affixed to and surrounding said cuvet ring having a generally concave inner surface arranged to restrain and confine the liquid separated from said cuvet ring within said annular collecting during rotation of said cuvet ring.

3. Apparatus in accordance with claim 2 wherein an additional collecting member is located below said annular ring member to receive liquid from said annular ring by gravity flow when said annular ring member ceases to rotate.
